UNITED STATES PATENT OFFICE.

HERMAN H. WOLTER, OF MERIDEN, CONNECTICUT, ASSIGNOR TO THE MILLER COMPANY, OF MERIDEN, CONNECTICUT, A CORPORATION OF CONNECTICUT.

DESIGN FOR AN ARM FOR BRIDGE LAMPS OR THE LIKE.

Application filed June 17, 1925. Serial No. 13,801. Term of patent 7 years.

To all whom it may concern:

Be it known that I, HERMAN H. WOLTER, a citizen of the United States, residing at Meriden, in the county of New Haven and State of Connecticut, have invented a new, original, and ornamental Design for Arm for Bridge Lamps or the like, of which the following is a specification, reference being had to the accompanying drawing, forming a part thereof.

Figure 1 is a side elevational view of the arm for bridge lamps;

Figure 2 is a diagrammatic plan view of the arm for bridge lamps, a portion of the ornamentation being omitted.

I claim:

The ornamental design for an arm for bridge lamps, or the like.

HERMAN H. WOLTER.
